(57) **CLAIM**

The ornamental design for a grill press, as shown and
described.

DESCRIPTION

FIG. 1 is an upper left front perspective view of a grill press
showing my new design;

FIG. 2 is a front elevational view of the same, with the rear
elevational view being a mirror image thereof;

FIG. 3 is a left side elevational view thereof, with the right
side elevational view being a mirror image thereof;

FIG. 4 is a top plan view thereof; and,

FIG. 5 is a bottom plan view thereof.

The broken lines in FIGS. 1 to 4 showing fastener means on
the handle of the grill press form no part of the claimed
design.
